UNITED STATES PATENT OFFICE.

VIRGINIO CAVALLINI, OF SPEZIA, ITALY.

SUBMARINE WITH DETACHABLE CONNING-TOWER FOR LIFE-SAVING PURPOSES.

1,159,745.

Specification of Letters Patent.

Patented Nov. 9, 1915.

Application filed July 1, 1914. Serial No. 848,406.

To all whom it may concern:

Be it known that I, VIRGINIO CAVALLINI, a subject of the King of Italy, residing in the city of Spezia, Province of Genoa, Kingdom of Italy, have invented certain new and useful Improvements in Submarines with Detachable Conning-Towers for Life-Saving Purposes, of which the following is a specification.

10 Ever since the first submarines were invented, the attention of builders was directed to the best means of bringing the crew to the surface in case the craft, owing to some damage to the hull, or through any other cause, were unable to come again afloat, being thus forced to remain stranded at the bottom of the sea. With this object in view, several methods have been proposed, chiefly based upon the principle of fitting on to the 15 submarine independent parts, detachable at will, consisting in floating bodies, buoys, or even actual boats, by means of which the crew, or part of it, might successfully reach the surface. The above mentioned idea is 20 no doubt very rational, but the application of said contrivances, in order to effectively insure the safety of the crew, proves generally so difficult and cumbersome as to be wholly unpractical, unless the dimensions 25 of the detachable parts are extremely limited, in which case only one or very few persons might avail themselves of this means of escape. It suffices, in fact, to look at any 30 type of submarine in order to come to the 35 conclusion that all these cumbersome contrivances, occupying a large portion of the free space on board, such as buoys or other floating apparatus capable of containing several persons, are quite out of question for 40 lack of space, while it would be impossible to apply them externally without altering the shape and dimensions of the hull and impairing the seaworthiness of the boat. According to the present invention, however, 45 it is proposed to make use, for life-saving purposes, of a part of the submarine itself, capable of containing the whole crew, namely the conning-tower, which is always applied to all craft of this type. The de- 50 tachable floating body is therefore nothing, in this case, but the conning-tower, on which is maintained the usual steering gear and the usual hatchway which allow access to the interior of the submarine. Its shape may 55 vary according to circumstances, in order to adapt it to the shape of the deck and to the

structure of the submarine. The body of the conning-tower may, moreover, be provided externally with light plates so as to perfectly round off the edges at its junction 60 with the upper structure of the submarine.

In the accompanying drawing, which illustrates by way of example a conning tower according to the present invention and its connections with the hull of the vessel: 65 Figures 1 and 2 are respectively a vertical longitudinal section on line $y-y$ of Fig. 2 and a top view of the conning-tower, partially uncovered in order to show better its internal construction. Fig. 3 is a vertical 70 transverse section of the same, on line $x-x$ of Fig. 2.

The conning-tower —1— is built of steel plates, or of other material, magnetic or not magnetic according to the requirements and 75 is so constructed as to be able to withstand the pressure of the greatest depth for which the submarine is intended. A hatchway —2— the cover of which may be shut or opened from both sides, gives access from 80 the outside.

One or more hatchways —3—, furnished with a double shutter —4—, which can be operated from either side, allow communication between the interior 5 of the conning-tower and the interior —6— of the submarine. These shutters —4— are of the type with bayonet-joint locking or of a similar type capable of resisting pressure from 85 both sides. The communication between the 90 conning-tower and the submarine is obtained as follows: a metal hatchway —3— is bolted to the resisting hull —7— of the submarine; the connection of this hatchway with the conning-tower might be effected by means of 95 a rigid metallic flange and bolts to be operated from the inside. In the drawing, is represented a far more rapid and safe system.

The hatchway body —3— ends on its 100 upper edge with a conical tapering —8—. To the bottom of the conning-tower is attached by means of a metal ring —9—, an elastic collar —10— of rubber or of any 105 other suitable material. This collar consists of a circular horizontal flange —10— which adheres to the bottom of the conning-tower to which it is connected by means of a flat metal ring —9— and of a vertical collar —10— which is inserted on the tapered end 110 of the hatchway body —3—. This vertical elastic collar is surrounded by a metal band

—11— connected with a shaft 11¹, which may be controlled from the inside of the conning-tower by means of the hand-wheel —12—. By turning this hand-wheel it is possible, by means of its threaded spindle —13—, acting on the worm-wheel —14—, to tighten the elastic band —10— against the conical opening —8— of the hatchway —3—. In correspondence with this hatchway are applied the two shutters —4—, the first on the hull —7— of the submarine, the second inside the conning-tower: these shutters are hermetically closed by means of a bayonet-joint or of any other joint which may be operated, from either side.

The conning-tower, Fig. 3, rests by means of blocks —15— riveted to its sides, upon as many blocks —16— connected with the body of the submarine. The contact surface of the blocks 15—16 is so inclined that the conning-tower gets easily detached even if the boat has heavily heeled. In correspondence with these blocks it is convenient, although not strictly necessary, to provide locking members —17— so as to insure the transversal rigidity of the connection in the event of the submarine being struck by cross-waves during its navigation on the surface. The bottom —18— of the conning-tower rests in a cradle shaped structure —19— superposed on the hull of the submarine. In the interior of the conning-tower is provided a longitudinal shaft —20— which ends at each of its extremities in a cross-piece —21— carrying two locking bolts —22— which may, gliding on an inclined plane, engage the stirrup —23— fastened to the submarine. The longitudinal shaft is divided into two halves connected by means of a sleeve —24— forming a screw-coupling with two threads in opposite direction engaging corresponding threaded portions at the ends of the two shafts. The sleeve is rotated by means of the hand-wheel —25—. This arrangement renders it possible to free together the bolts from the stirrups —23—, which is of the greatest importance in case the submarine should find itself in an inclined position. The shaft rests on supports —26— and passes through two watertight recesses —27— in which are placed two drums loosely mounted on the shaft —20— and around which is wound the steel cable —29— connected with the hull —7— of the submarine.

The drums —28— loose on the shaft —20—, carry on their hub a worm wheel 30 engaging a perpetual screw —31— which allows to rotate the drum at will. The object of these drums is to facilitate the coming to the surface with the conning-tower, regulating at will the speed of the ascension. In order to detach the conning-tower and to come to the surface with it, the following operations are to be performed. Supposing the submarine to be resting at the bottom of

the sea, the crew passes from the hull into the interior of the conning-tower through the hatchways —3— closing afterward both the shutters at the interior of the submarine and those inside the conning-tower. The crew then takes up a position around the walls of the conning-tower between the stanchions, ready for the operations of detachment which are ordinarily the following: (1) Freeing the elastic collar —10— by means of the hand-wheel —12—. (2) Withdrawal of the locking wedges —17—. At this moment the conning-tower is ready for the detachment which may take place instantaneously by means of the simple rotation of the hand wheel —25—, having for effect the contemporaneous disengagement of the four large locking bolts —22— from the stirrups —23—.

The regulation of the ascensional movement is effected by means of the hand-wheel with the worm screw —31—, which allows the wheel —30— fastened to the drum —28— to revolve, thus unwinding the cable —29—. This cable is fastened at one of its ends to the submarine while at the other end is freely wound on the drum, so that it may be abandoned, after having been fully unwound if, on arriving at the surface, it is desired to have the conning-tower completely free and independent from the submarine. The various operations may easily be carried out with the crew keeping their places. The conning-tower, as has already been said, preserves its ordinary functions as steering place, and in it are therefore placed an ordinary navigating compass —32—, the tell-tale —33— with the steering-wheel —34— and the transmission —35— —36— —37— —38—, which, as seen in the drawing, is connected with the shaft —39— which reaches in the interior of the hull and in no way interferes with the detachment of the conning-tower, either if the submarine be longitudinally or transversally inclined. In the longitudinal direction the conning-tower, according to the shape of the superstructure of the submarine, will carry light connecting plates so fashioned as not to interfere with the detachment of the conning-tower in whatever manner the vessel may be heeling over.

What I claim is:

1. Submarine vessels comprising in combination with the hull: a detachable conning-tower; hatchways allowing communication between the conning-tower and the hull, each consisting of a cylindrical body fastened to the deck of the vessel, and terminating, in their upper part, with a tapered end; two shutters for each of the hatchways, placed at the two ends of the cylindrical body of same, hermetically closed and capable of being opened both from the inside and from the outside; an elastic collar set

upon the tapered end of each hatchway body; a metallic band around the said collar, and means to press the band against the elastic collar.

5. 2. In a submarine vessel of the class specified a plurality of blocks secured around the lower edge of the vertical wall of the detachable conning-tower on its outside; a corresponding number of blocks fastened to the 10 deck of the vessel, of square section, having their face turned toward the conning-tower inclined so as to exactly fit with the corresponding face of the blocks first named; and locking members which traverse the said 15 couples of blocks.

3. In a submarine vessel of the class specified having a detachable conning tower, the base of which fits to the deck of the submarine vessel, means for longitudinally connecting the tower with the hull of the submarine vessel, comprising a horizontal shaft placed longitudinally inside the conning tower and divided into two portions, the projecting ends of which are threaded in opposite directions, a sleeve likewise threaded 20 in opposite directions and acting on the two portions of the aforesaid shaft, connecting 25

them and causing them to move simultaneously forward and backward, a cross piece at the free end of each of said portions, two locking bolts provided at the ends of each cross piece disposed to embrace the hatchway and allow communication between the tower and the submarine vessel, and stirrups secured to the deck of the submarine adapted to receive said locking bolts. 30 35

4. In a submarine vessel of the class specified a horizontal shaft placed longitudinally in the conning-tower and divided in two parts, an intermediate sleeve connecting said parts, two drums loosely mounted on the two parts of the shaft, a steel cable of suitable length wound around each drum, having its outer end fastened to the deck of the submarine. 40 45

In testimony whereof I have affixed my signature in the presence of two subscribing witnesses.

Rome, the 29th day of May, 1914.

VIRGINIO CAVALLINI.
